UNITED STATES PATENT OFFICE.

GEORGE F. POE, OF MILFORD, INDIANA.

RATCHET-WRENCH.

SPECIFICATION forming part of Letters Patent No. 462,995, dated November 10, 1891.

Application filed May 13, 1891. Serial No. 392,622. (No model.)

To all whom it may concern:

Be it known that I, GEORGE F. POE, a citizen of the United States, residing at Milford, in the county of Kosciusko and State of Indiana, have invented certain new and useful Improvements in Ratchet-Wrenches; and I do hereby declare the following to be a full, clear, and exact description of the invention, such as will enable others skilled in the art to which it appertains to make and use the same.

My invention consists in a new and improved ratchet-wrench, which is capable of adjustment so that it can be turned in either direction, either to tighten the nut or loosen the same, and which is further provided with interchangeable wrench-jaws of different sizes, so that a wrench socket or jaw can be placed in the wrench to fit any-sized nut; and the invention will be hereinafter fully described and claimed.

Referring to the accompanying drawings, Figure 1 is a perspective view of my new and improved ratchet-wrench. Fig. 2 is a similar view showing the removable wrench-socket and the ratchet-collar removed. Fig. 3 is a longitudinal sectional view of the same, taken on line $\alpha\alpha$ of Fig. 1. Fig. 4 illustrates in detail the interchangeable wrench jaws or sockets.

Referring to the several parts by their designating-numerals, 1 indicates the body of my new and improved ratchet-wrench, which is provided with a suitable handle 2. The body is formed with the longitudinal slot or opening 3, and in the outer ends of the side plates 4 are formed the opposite openings 5 and 6. In the sides of the longitudinal opening 3, formed in the body of the wrench, are centrally pivoted the ratchets 7 and 8, and in the outer end of the body is mounted the circular ratchet-collar 9, which is formed with the series of exterior teeth and has a square opening 10 formed through its center. A spiral spring 20 is arranged transversely in the lower part of the opening 3, with its ends bearing against the inner ends of the centrally-pivoted ratchets 7 and 8. It will be seen that this spring will normally press the outer locking ends of the said ratchets inward.

The interchangeable wrench jaws or sockets illustrated in detail in Fig. 4 are formed

with end sockets 11 of different sizes to fit nuts of varying sizes. The stem of each socket is formed with a central bore 12, leading from the socket 11, for the reception of the end of a bolt on which the nut being screwed or unscrewed is mounted, the center of this stem 13 being square in cross-section and of such size as to fit rather loosely in the square opening 10 of the ratchet-collar 9. At each end of this square center the stem is formed with the round bearing-surfaces 14 15, adapted to fit and turn, respectively, in the round openings 5 6. Both ends of the clutching device may be formed with sockets, as shown in one of the clutches illustrated in Fig. 4.

On the side of the flat stem 13 is secured an outwardly-curving spring 16, and when the straight stem of the clutch is pushed into the opening 10 in the ratchet-collar this spring, pressing tightly against the inner side of the said collar, will firmly hold the removable jaw in the collar and prevent its falling out, while it can be pushed out by the hand, when desired, with a slight effort.

It will be seen that by the above-described construction the nut in the wrench can be readily pushed out and a clamping-jaw of the desired size for the particular nut to be handled can be readily slipped into the wrench in operative position.

17 indicates a movable ring, which fits around the lower end of the wrench-body just below the lower ends of the ratchets 7 8. On the upper side of this ring is formed a lug 18. By turning this ring to the right until the lug 18 passes over the lower end of the ratchet 7 the upper end of the said ratchet will be pressed out, and the wrench can then be applied to a nut and will turn the same to the left and loosen or unscrew it. By turning the ring 17 to the left until the lug 18 passes over the lower end of the ratchet 8 the outer end of the said ratchet will be pressed out, and the ratchet can then be applied to a nut and will turn the same to the right and tighten or screw the same on its bolt. By turning the ring 17 so that the lug 18 will be clear of both ratchets the wrench can be used as an ordinary wrench, the two ratchets holding the ratchet-collar 9 from turning in either direction. A square recess 19 may be formed in

the extended end of the rear side 4 to fit small nuts.

From the foregoing description, taken in connection with the accompanying drawings, 5 the construction, operation, and practical advantages of my new and improved ratchet-wrench will be readily understood. It will be seen that this wrench is exceedingly convenient and handy in use, as the clamping jaws 10 or sockets can be changed to fit nuts of various sizes, and by the peculiar construction of the pivoted spring-actuated ratchets 7 8 and the ring 17 and its lug 18 the wrench can be adjusted to work in either direction and still work as 15 ratchet-wrench. By turning the ring 17 to the right until the lug 18 passes over the lower end of the ratchet 7 the upper end of the said ratchet will be pressed out and the wrench can be applied to a nut and will turn the same 20 to the left and will loosen or unscrew it. By turning the ring 17 to the left until the lug 18 passes over the lower end of the ratchet 8 the outer end of the said ratchet will be pressed out, and the ratchet can then be applied to a 25 nut and will turn the same to the right and tighten or screw the same on its bolt. By turning the ring 17 so that the lug 18 will be

clear of both ratchets the wrench can be used as an ordinary wrench, the two ratchets holding the ratchet-collar 9 from turning in either 30 direction.

Having thus described my invention, what I claim, and desire to secure by Letters Patent, is—

The herein-described ratchet-wrench, comprising the body 1, provided with a handle 2, a longitudinal slot or opening 3, the plates 4 4, having the openings 5 6, the centrally-pivoted ratchets 7 and 8, the circular ratchet-collar mounted in the outer end of the body and 40 formed with the square central opening 10 and a series of exterior teeth, the spiral spring 20, interposed between the inner ends of the ratchets 7 and 8, and the movable ring 17, provided with the lug 18 and fitted around the 45 lower or inner end of the wrench-body, substantially as specified.

In testimony whereof I affix my signature in presence of two witnesses.

GEORGE F. POE.

Witnesses:

EDWIN W. HIGLER,
L. R. MILES.
